UNITED STATES PATENT OFFICE.

JAMES R. CALDWELL, OF NEW HAVEN, CONNECTICUT, ASSIGNOR TO THE SEAMLESS RUBBER COMPANY, INC., OF NEW HAVEN, CONNECTICUT, A CORPORATION OF MASSACHUSETTS.

DIPPING MACHINE.

Application filed June 16, 1921. Serial No. 478,116.

To all whom it may concern:

Be it known that I, JAMES R. CALDWELL, a citizen of the United States, and a resident of New Haven, county of New Haven and 5 State of Connecticut, have invented an Improvement in Dipping Machines, of which the following description, in connection with the accompanying drawings, is a specification, like characters on the drawings representing like parts.

This invention relates to a machine for applying coating to objects by dipping them one or more times in a bath of suitable material. This process is utilized in forming 10 small rubber objects such as the nipples of nursing bottles, finger cots, toy balloons and the bulbs of medicine droppers, suitable forms being repeatedly dipped into a solution of rubber cement which, drying on the 15 forms, builds up the desired article. The embodiment of the invention here shown is particularly designed for this use and the purpose is to provide an efficient and rapidly 20 operating machine which will be of great 25 flexibility to meet the varying conditions of use met in practice.

My invention will best be understood by reference to the following description of the embodiment thereof shown by way of example in the accompanying drawings, 30 wherein:

Fig. 1 is a front elevation of the machine partly broken away;

Fig. 2 is a section on the line 2—2 of 35 Fig. 1;

Fig. 3 is a section on the line 3—3 of Fig. 1 on an enlarged scale;

Fig. 4 is a detail of a portion of Fig. 3 on a still larger scale;

Fig. 5 is an end elevation of a portion 40 of the machine as seen from the right of Fig. 1;

Fig. 6 is a section on the line 6—6 of Fig. 5; and

Fig. 7 is a section on the line 7—7 of 45 Fig. 1 on an enlarged scale.

Referring to Fig. 1, the machine embodies a dipping tank 9 and a form carrier 11, the two being movable toward and from 50 one another in a vertical direction so that forms on the carrier may be dipped into the liquid in the tank and in the present embodiment of the invention the tank is stationary and the carrier movable up and

down. To move the carrier 11 up and down 55 it is mounted as a whole in the vertically reciprocable frame comprising the cross bar 13 and the depending side bars 15, the latter as best shown in Fig. 7 being provided with channeled guides which receive the flanges 60 of the vertical T irons 17. The frame guided on the T irons 17 may be moved vertically by means of a suitable hoist comprising the cables 19 secured to the members 15 and wrapped about drums 21 on the overhead 65 shaft 23 which is adapted to be driven by suitable power in the manner hereafter described.

The form carrier 11 is preferably designed to accommodate several sets of forms and 70 may take the form clearly shown in Figs. 1 and 3 of a skeletonized prism, conveniently square in section as indicated, and supported by a shaft 25 journalled in the depending members 15. Referring to Fig. 3, the forms 75 27 for the articles to be dipped may be mounted on suitable boards 29 which are clamped to the faces of the prismatic form 11 and for this purpose each face may be provided at one end with the overhanging 80 flange 31 to receive one edge of the board and along the opposite edge there is hinged an angle iron 33 which may be swung downwardly on its hinge to permit the board to be inserted under the flange 31 with a button-holing motion and then closed to the 85 position shown in Fig. 3 to retain the board in position. To hold the hinged angle iron 33 in position latches 35 may be provided adapted to swing up behind the same to the 90 position shown in Fig. 4, the latches 35 closing in behind the keepers 37.

When any single set of forms is being dipped, that face of the form carrier is substantially horizontal, paralleling the surface of the liquid in the tank 9. To insure this parallel position and consequent even immersion of the forms and to hold the form carrier in this position, suitable locking means may be provided, preferably effective only when the carrier is near dipping position. Herein I have shown mounted on the shaft 25 at one end of the carrier 11 the enlarged polygonal wheel 39 considerably greater in size than the carrier and, as shown in Fig. 1, mounted laterally of the tank 9 so that as the carrier lowers, the edge of the wheel 39 may pass downwardly at the 100 105

side of the tank and permit forms on the carrier 11 to enter the tank in spite of the larger size of the wheel 39. The wheel 39 is preferably polygonal as shown and may 5 have twice as many sides as the base of the prism which forms the carrier, that is, being octagonal in the present instance and certain of these sides are parallel with the sides of the carrier, thus providing a guide 10 and indicator of the position of the carrier itself since a horizontal position of the side of the wheel 39 will indicate a corresponding horizontal position of the carrier 11. At the same time the fact that the polygon 15 has more sides than the base of the prism gives the wheel 39 a finished wheel-like form and while providing an adequate mechanical advantage when the wheel is used as a turning member as hereafter described, 20 restricts the area through which the wheel sweeps.

Suitable means cooperating with the wheel 39 are provided for locking the carrier in position and, as best shown in Figs. 25 2 and 1, those sides of the wheel parallel with the faces of the carrier 11 may be provided on the outer side with guides, each 30 preferably formed of a pair of springs 41 secured at one end and thence inclining outwardly and toward each other and having inturned ends passing through suitable slots in the wheel, these inturned ends defining between them a radial opening which is 35 adapted to receive a stationary guide 43 disposed beside the tank, and provided with a bevelled end facing the wheel as shown in Fig. 1.

If the wheel 39 approaches the guide 43 in 40 a position somewhat displaced circumferentially from that illustrated in Fig. 2, the bevelled end of the guide 43 will strike a spring 41 and wedge it inwardly permitting the continuing descent of the wheel. The operator may seize the wheel 39, which 45 provides a powerful leverage, and bring it into the proper position and the guide will slide along the incline provided by the spring until it snaps into the slot between the two springs. The edge of the guide 43 below the 50 bevelled end substantially coincides with the face of wheel 39 as shown in Fig. 1 and as the forms reach dipping position the wheel is necessarily locked by the engagement of the guide in the slot and the form carrying 55 board disposed parallel with the surface of the liquid in the tank 9.

I will next describe the mechanism here shown for raising and lowering the form carrier which preferably provides for a 60 slow speed and a high speed in raising and lowering. Herein (see Fig. 1) the drum shaft 23 is adapted to be driven by the worm shaft 45, the worm acting as an effective locking means for the shaft when no power 65 is applied, and the worm shaft takes motion

through the bevel train 47 from a shaft 49 on which is a large pulley 51 and a small pulley 53. The shaft 49 is driven by a suitable connection (see Figs. 5 and 6) from a reversible electric motor 55, conveniently secured to the ceiling, which is adapted to drive in one direction or another the shaft 57 mounted on hangers on the ceiling and carrying the small loose pulley 59 and the large loose pulley 61 which may be relatively 70 clutched to the shaft by motion of the clutch 63 which also has a neutral position in which both pulleys are loose. In the neutral position of the clutch, of course, no power is transmitted to the hoist shaft 23. The small 75 pulley 59 is belted to the large pulley 51 on shaft 49 and drives that shaft with a relatively slow speed in such a way as either to wind up the cables 19 on their drums or unwind them in accordance with the direction of rotation of the reversible motor. The large pulley 61 is belted to the small 80 pulley 53 on the shaft 49 and provides for driving that shaft at a relatively high speed. 85

Means are provided whereby the form carrier 11 may be rotated, preferably forward and back, at an elevated position thereof in order to facilitate the drying of the coating on the forms. For this purpose the shaft 25 of the carrier may support at its outer end 90 a gear 65 which, as best shown in Fig. 2, is adapted to roll into contact with the laterally disposed pinion 67 when the carrier rises to the position shown in that figure. The pinion 67 (see Figs. 1 and 3) takes its 100 motion from an electric motor 69 connected thereto by an automatic reversing mechanism 71. This mechanism may be substantially like that illustrated in the patent to Henrici, 1,316,093, September 16, 1919, and 105 it is therefore unnecessary to illustrate it in detail in this place. Suffice it to say that it provides for periodically reversing the motion of the shaft carrying the pinion 67. This may be effected as in the patent referred to by reversing the direction of rotation of the motor 69. The form carrier 11 may thus be rotated a predetermined number of revolutions, say for example four, in 110 a counterclockwise direction, will then rotate the same number of revolutions in a clockwise direction and so on until the motor is shut off or the gear 65 moved out of engagement with the pinion 67. 115

The operation of the device is as follows. 120 The tank 9 is filled to a suitable level with a rubber solution. The operator fills the sides of the carrier 11 with boards 29, (see Fig. 3) on which are mounted the forms to be dipped, locking them in place by folding the angle iron 33 over the edge of the board and locking it by the latch 35 which enters behind the keeper 37. The parts being in the position shown in Figs. 1 and 2, the motor 55 (see Fig. 5) is started, the clutch 63 125 130

(Fig. 6) is thrown into engagement with the large pulley 61 to rotate the drum shaft 23 at a relatively high speed and lower the form carrier quickly toward the tank. Just before the forms enter the tank the clutch 63 is thrown into engagement with the small pulley 59 to cause the forms to enter the cement at a relatively slow speed which is proper for the dipping operation. As the form carrier approaches the tank if one of the faces thereof is not parallel with the surface of the liquid in the tank, the operator will seize the large wheel 39 and turn it slightly by hand until the guide 43 properly engages between the springs 41 (see Fig. 2). It will be noted that while the frame is being lowered it is entirely free to rotate and is not connected in any way with any driving mechanism and may be turned by hand on its horizontal axis without any difficulty.

When the forms have entered the solution in the tank to the proper depth the operator reverses the motor 55 and causes the frame 11 to rise at the slow speed. Immediately when the forms are withdrawn from the viscous cement it tends to run down on the same and form a drop like a rudimentary icicle. To prevent this, as soon as the frame rises clear of the cement the operator grasps the wheel 39 and reverses the frame 11 so that the board just dipped will be at the top. The hoisting motion of the frame may be availed of to assist in this operation. At about the same time the clutch 63 is thrown and the frame rapidly elevated to the position shown in Fig. 2 where the gear 65 will engage pinion 67 and, when the frame has reached this position, clutch 63 is thrown to neutral and the vertical motion of the frame halted.

The operator then energizes motor 69 and the frame 11 will be rotated a desired number of times in one direction and then a desired number of times in the other direction until the coating is sufficiently set. The rotation of the carrier facilitates the congealing of the coating and the periodical reversal of this rotation prevents the viscous cement from flowing over toward one side of the form due to its inertia during the rotation thereof and the reaction of the air against it and insures the coating being dried in a layer of uniform thickness.

After the coating is set the motion of the motor 69 is halted and the frame lowered again to dip a new set of forms, the operator turning the frame by means of the enlarged operating wheel 39 to present an undipped set to the tank if such a set is not already so presented and the cycle of operations is repeated until all the forms are coated and if necessary or desired repeated for each set of forms until a proper thickness of material is built up. The boards 33 may then be removed and new forms substituted.

The mechanism described is very efficient in its operation and very flexible in its capabilities as it provides adequate mechanical means for carrying out the operations without preventing proper variations and adjustments to be made to meet the varying requirements of practice. As an example of such flexibility will be noted the mounting of the form carrier 11 so that after it starts lowering it is entirely free to be revolved by hand in a manner conveniently provided for by the enlarged wheel 39 to adjust or position the form carriers relatively to the tank without any resistance of attached mechanism opposing such motion. The operation of the carrier by means of a cable hoist with a two speed drive permits a variable dipping and enables the operator to change from high to low speed at the best point as dictated by the particular work at hand. The automatic reversal of the rotation of the form carrier in cooling position is the most efficient method for providing a smooth and uniform coating and at the same time causing rapid congealing thereof.

Having thus described in detail the particular embodiment of my invention shown by way of example in the accompanying drawings, what I claim as new and desire to secure by Letters Patent I shall express in the following claims:

1. A machine of the class described comprising, in combination with a tank, a vertically movable form carrier freely rotatable about a horizontal axis and means for connecting said carrier with power driven rotating means in an elevated position thereof.

2. In a machine of the class described, in combination with a tank, a form carrier movable upwardly and downwardly from and to the tank and freely rotatable on a horizontal axis, power driven rotating means cooperating with the carrier in an elevated position thereof and locking means cooperating with the carrier solely in the lower part of its path to hold it against rotation in the lower part of its path.

3. In a machine of the class described, in combination with a tank, a form carrier movable upwardly and downwardly from and to the tank and freely rotatable on a horizontal axis, power driven rotating means cooperating with the carrier in an elevated position thereof and an enlarged wheel on the axis of the carrier disposed beyond the tank and providing means for turning the carrier by hand.

4. In a machine of the class described, in combination with a tank, a form carrier movable upwardly and downwardly from and to the tank and freely rotatable on a horizontal axis, power driven rotating means cooperating with the carrier in an elevated

position thereof, an enlarged wheel on the axis of the carrier disposed laterally of the tank and a locking member cooperating with said wheel to hold the carrier against 5 rotation in the lower part of its path.

5. A machine of the class described comprising, in combination, a dipping tank, a form carrier, means for moving one to and from the other and automatically reversing 10 means for revolving the form carrier.

6. A machine of the class described comprising, in combination, a dipping tank, a rotatable form carrier, means for moving one to and from the other and power means 15 for rotating the carrier arranged to permit reversal of the direction of rotation.

7. A machine of the class described comprising, in combination, a dipping tank, a rotatable form carrier, means for moving one to and from the other and means for 20 revolving the carrier a determined number of revolutions in one direction and thereafter in the opposite direction.

8. A machine of the class described comprising, in combination, a dipping tank, a form carrier, a hoist for raising and lowering one of them comprising a drum shaft, a power shaft and alternatively operable 25 driving connections of different speed ratios between said shafts.

9. A machine of the class described comprising, in combination with a tank, a freely rotatable form carrier, means for raising and lowering the carrier having two 30 speeds effective at will and means for connecting the carrier with rotating mechanism in an elevated position thereof.

10. A machine of the class described comprising, in combination with a tank, a prismatic form carrier freely rotatable about a horizontal axis, means for raising and lowering the carrier having two speeds effective 35 at will and means for connecting the carrier with rotating mechanism in an elevated position thereof.

11. A machine of the class described comprising, in combination with a tank, a prismatic form carrier freely rotatable about a horizontal axis, means for raising and low-

ering the carrier having two speeds effective 50 at will, means for connecting the carrier with rotating mechanism in an elevated position thereof and locking means holding it against rotation with a face thereof horizontal in the lower part of its path. 55

12. In a machine of the class described, a prismatic form carrier rotatable on a horizontal axis and a hand wheel associated therewith comprising a polygon larger than the base of the prism, the number of sides 60 of the polygon being a whole multiple of the number of sides of said base, certain of the former sides being parallel to the latter.

13. In a machine of the class described comprising, in combination, a dipping tank and a form carrier, one being movable toward and from the other, means for positioning the carrier when near the tank comprising yieldably mounted inclines on one 70 element defining an opening between them and a guide adapted to enter the opening having a bevelled end.

14. In a machine of the class described comprising, in combination, a dipping tank 75 and a form carrier, one being movable toward and from the other, means for positioning the carrier when near the tank comprising a plate on one element, springs thereon having inturned ends and presenting 80 a pair of inclines defining an opening between them and a guide adapted to enter the opening having a bevelled end.

15. In a machine of the class described comprising, in combination, a dipping tank 85 and a form carrier, one being movable toward and from the other, means for positioning the carrier when near the tank comprising a pair of inclines associated with the carrier and defining a space between them 90 and a guide fixed in a vertical plane and having a bevelled end, there being provision for relative movement of the parts in horizontal planes.

In testimony whereof, I have signed my 95 name to this specification.

JAMES R. CALDWELL.
